UNITED STATES PATENT OFFICE.

ANTOINE BARNAY, OF VILLENEUVE ST. GEORGES, FRANCE.

AUTOMATIC SWITCHING SYSTEM.

Application filed July 24, 1923. Serial No. 653,568.

To all whom it may concern:

Be it known that I, ANTOINE BARNAY, a citizen of the French Republic, residing at 126 Avenue de Valenton à Villeneuve St. Georges, Seine and Oise, France, have invented certain new and useful Improvements in Automatic Switching Systems, of which the following is a specification.

The present invention relates in general to 10 an automatic switching system of the kind generally known as a "step by step" system, employed particularly in telephony, but capable to be employed generally in any system of intercommunication either electrical 15 or electromagnetic.

The main object of the invention is to produce a new and improved system of selection whereby the operation of the selectors, in response to impulses of a calling device 20 is realized in the same way as the trunk hunting movement these two movements being produced by the same means.

Another object of the invention is to employ only one type of switch, of simple 25 mechanical construction, robust, having very little inertia, for the different series of switches such as preselectors, finder switches and selectors.

A further object of the invention is to provide an auxiliary organ individual to a selector or common to a number of selectors of the same category of very little inertia 30 which is operated by the impulses of the calling device and which in turn directs the group hunting movement of the selector or 35 selectors.

Lastly, another object of the invention is to provide means for grouping the lines connected to the banks of the different 40 switches in the most economical manner according to the needs of the traffic.

Referring to the drawing which represents a preferred form of the invention,

Fig. 1 is a diagram of the different organs 45 used to establish a connection.

Figs. 2, 3 and 4 are circuit diagrams of the organs represented in Fig. 1 and should be joined together at the lines A—A and B—B.

Figs. 5, 6 and 7 are diagrams showing 50 different connections between the auxiliary control switches and the selector switches.

Fig. 8 is another circuit diagram in which 55 the control switches are common to a certain number of selectors.

The organs employed to establish a connection and represented in Fig. 1 consist of the calling subscriber's telephone P, a line and cut off relay R, a finder switch A, a preselector B, a hundred's selector D, a line selector E, the line and cut off relay of the called line R' and the called subscriber's telephone P'. The system represented is a three digit system, for a four digit system, there would be another selector, the thousand selector, similar to the selector D, introduced between the calling line and the line selector E, for 5 digits two selectors between the calling line and the connector, etc. . . . and finally, for a two digit system the selector D would be omitted. A finder switch A and a preselector B are shown but according to the traffic to be handled it might be economical to use only one or the other of these two organs. The progression of the call is the same, excepting for the transmission mechanically and electrically of the impulses sent out by the calling device, as in the best known "step by step" systems.

The subscriber's stations P and P' may be one of any of the well known types having a calling device which opens and closes the line circuit a number of times equal to the 55 digit to be sent.

The line and cut off relays R are individual to each line, and each line is multiplied on the banks of a group of finder switches and also on the banks of the line selectors 90 which have access to the group of one hundred lines, in which is located the line considered.

The finder switch A and the preselector B consist of a group of relays and two rotary switches K₁ and K₂; the selector D consists of a group of relays and a rotary switch K₃ similar to the rotary switches K₁ and K₂, and an auxiliary or control switch C.

The switches represented at K₁, K₂, K₃ and K₄ are step by step rotary switches of the type in which the wipers move in a forward direction only. In further explanation of these switches it should be stated that they are of the type in which the wipers are advanced when the stepping magnet retracts its armature rather than when the stepping magnet is energized. Their banks consist of a certain number of semi circular rows of contacts to which may be connected either the subscribers or trunk lines, and on the selectors an extra row or two of auxiliary

contacts are provided to control the rotary movement of the switch. Each rotary switch is provided with as many sets of wipers as there are rows of contacts in its bank, these wipers being either double or single; in the first case when one end of the wipers quits the last contact of a row, the other end engages the first contact of the same row. In the second case, the wipers are in contact with the bank only during half a revolution, one set of wipers being secured to the shaft at 180 degrees from the other, and only one set of wipers is in contact with the banks at the same time.

For a 50 line rotary switch, the bank consists of three rows of 50 contacts each and 3 double wipers, for a 100 line switch the bank consists of 6 rows of 50 contacts each and either six single wipers or 6 double wipers, and a relay associated with the wipers to select one of the two sets of wipers. This latter arrangement is preferable as it diminishes by half the rotation of the switch. For a 200 line switch the bank consists of 12 rows of 50 contacts each and 12 single wipers are used with a wiper choosing relay. For the selectors, in all cases an extra row of contacts on the bank and an extra wiper are provided to control the rotation of the switch.

Each selector is provided with a set of off normal springs which are operated as soon as the wipers leave their normal position.

In Fig. 2 the line finder A is a 100 line rotary switch having two sets of three double wipers, the preselector B is a 50 line rotary switch with 3 double wipers and the selector D has two sets of three double wipers and an extra wiper with its associated row of bank contacts. The control switches such as C, associated with the selectors, are of the same general construction as the previously described rotary switch K_1 , K_2 , K_3 and operates in the same manner. They are much smaller than the rotary switch K_1 , K_2 , K_3 and are provided with two or more rows of 11 contacts each, and have a set of off normal springs which are operated when the wipers leave their normal position.

The control switch C, Fig. 2, associated with the selector D is provided with two rows of 11 contacts each, arranged in such a way that the contacts occupying corresponding positions in the two rows, are connected electrically by the wiper.

The mechanical construction of these rotary switches is not an object of the present invention.

The Fig. 3 is the circuit diagram of the line selector E with its two associated control switches C_2 and C_3 and its rotary switch K_4 . These organs are similar to those of the hundred's selectors shown in Fig. 2; the only difference between the line selector and

the hundred's selector is the arrangement of the circuits.

The Fig. 4 represents a rotary line selector, i. e. a selector which after being directed to a group of lines by two trains of impulses is capable to select and connect with an idle line in the group, the selection of an idle line in a group being automatic and each group of lines being determined and limited by the resistance of the cut off relay of the last line of the group which is less than that of the other cut off relays associated with the other lines of the same group. To facilitate the grouping of the lines, the cut off relays such as R_2 , R_3 and R_4 of the lines, which are served by a rotary line selector, are provided with an extra terminal connected to the left hand end of the winding of the cut off relays. The test wire is connected to this middle terminal when there is only one line, or to the middle contact of the last line when there are several lines listed under one number. The test wire is connected to the end terminal on all the other lines of the group.

Fig. 5 is a diagram showing the connections between the control switch and the row of control contacts of a thousands or hundreds selector which has access to ten different groups of trunk lines and each group of trunk lines having ten trunks. Supposing that the selector is a hundreds selector; in this case the control wires for the 1st. and 2nd. hundreds, 3rd. and 4th. hundreds, 5th. and 6th. hundreds, 7th. and 8th. hundreds, 9th. and 0 hundreds, are connected together on the bank of the control switch. These five control wires are connected to five series of 10 contacts on the row of control contacts in the bank of the rotary switch K, in such a way that when the digit 1 or 2 is dialled, the selector only rotates to find an idle line, when the digit 3 or 4 is dialled, it rotates over ten contacts before beginning the trunk hunting movement and so on. For the digits 9 or 0, the selector rotates over 40 contacts before beginning the trunk hunting movement. The selection between the odd or even digit is obtained by a wiper selecting relay as will be described in the detailed circuit description further on. After the wipers are directed to the first set of contacts of a group of trunks by the control switch which is operated by the impulses of the calling device, an idle trunk in the group may be selected by the automatic rotation of the wipers the control wire for the group being connected to the ten contacts of the control bank in the chosen group.

Fig. 6 is a diagram representing an uneven grouping on a ten thousand selector in a multi-office telephone system. It is assumed that there are 60,000 subscribers' lines in the system, distributed amongst six dif-

ferent offices having 10,000 lines each, and the subscribers being numbered from 20,000 to 79,999.

The 2nd. and 3rd. ten thousands subscribers are supposed to be located in offices which have a very heavy traffic with the office being considered, from which the necessity to employ secondary line switches.

If the traffic conditions are such as to necessitate 750 trunks between the two offices in one group, this groupment may be obtained by employing secondary line switches each having a capacity of 50 trunks and the trunks from the selector banks in groups of 15. If it were necessary to have only 650 or 700 trunks, the trunks from the selectors banks would be arranged in groups of 13 or 14.

It is assumed that the traffic with the 4th and 5th ten thousand is not very heavy and instead of employing secondary line switches, it is more economical to have the trunks from the selector bank in groups of 25.

It is further assumed the 6th and 7th ten thousand are two offices in the same building and as the cost of the inter office trunk lines is not preponderating, the trunk from the selector banks will be arranged in groups of 10.

This simple example is chosen to show the advantages to be gained by varying the size of the different trunk groups when it can be done easily without too many complications, which is the case in this system. It is not necessary to have any two groups alike, for example, in providing two rows of control contacts, 10 groups of trunks each having a different number of trunks may be obtained.

In general there may be 50, 100, 150 or 200 trunks in a selector bank and these trunks may be arranged in any number of groups between 1 and 10.

Likewise, in another office of the supposed multi office system, the traffic may be distributed in an entirely different way than in the office considered and an arrangement of the trunk groups entirely different would be more economical.

Fig. 7 is a diagram showing the connections between the control switches and the control contacts of a line selector. The tens control switch C_2 has five wires (one for two tens consecutive) connected to the first contact of each group of ten contacts in the row of control contacts of the bank of the rotary switch K the selection of the odd or even tens being obtained by a relay.

The units control switch C_3 is connected by 9 wires (the first contact is not connected as it does not require the rotation of the selector) to the nine remaining contacts in each one of the 5 groups of tens control contacts. Normally the line selector has a

capacity for 100 lines but its capacity may be doubled when it connects with subscribers having several lines listed under one number. In this case, a second row of control contacts on the bank of the rotary switch 70 is necessary.

Before entering into the detailed circuit description a general outline of the operation is as follows:

When the receiver is removed at the calling station, the calling line is extended to a selector (hundreds selector in a 3 digit system, thousands selector in a 4 digit system, etc. . . .) by means of a finder switch or a preselector or the two organs acting together.

Responsive to the first train of impulses sent by the calling device, the control switch takes a position corresponding to the impulses received and places a battery potential on a control contact of the bank of the main rotary switch so as to stop the latter on the first trunk of the group determined by the first train of impulses. The main rotary switch does not wait until the end 90 of the train of impulses before commencing to operate. As soon as the control switch reaches a position that determines a movement, the main rotary switch commences to operate and continues until the 95 control wiper reaches the contact which is connected to the control switch. After reaching the aforementioned contact, the automatic trunk hunting movement begins. When an idle trunk is found, the calling line 100 is extended to the next serially related selector and the same operation is repeated. When the final or line selector is reached, the operation is a little different from the other series of selectors, as in the line selector two trains of impulses are necessary 105 to determine the final position of the wipers. For this purpose, two control switches are provided, one for the tens digits the other for the units digit.

The first control switch 110 directs the wipers to the tens group corresponding to the impulses received for the tens digit and the second, operated by the unit digit impulses directs the wipers on to the particular line of the tens group already chosen. In the case of a rotary line selector, after finding the first line of a group of lines having the same number, the line selector selects an idle line in the group, if there is one, and in case all the lines are 120 busy, gives a busy signal to the calling subscriber.

In the present system, an idle line is identified by the presence of negative battery 125 on the test wire, and a line tests busy if the negative is not connected to the test wire, therefore the so called "dead lines" i. e. the lines not in service give automatically the busy test when an attempt is made to connect with them.

The general object and scope of the invention having been pointed out, the operation of the apparatus involved will now be described more in detail and for this purpose, it will be assumed first that the subscriber at station P, Fig. 2, desires to establish a connection with the subscriber at station P', Fig. 2 whose telephone number is 903. When the receiver is removed at station A a circuit is completed for the relay 2, from ground, contact 6, the line and the subscriber's station in series, the contact 7, the winding of relays 2 to battery. Relay 2 is energized and a contact 4 places ground on the starting wire of the finder switches by the contact 9; and at the contact 3 connects the low resistance winding of relay 5 to the test contacts of the line finder banks.

The relay 33 of the finder A is energized by the ground on the starting wire, over the circuit ground, contact 4, contact 9, contact 45, winding of relay 33 to battery. Relay 33 energized closes the circuit of the rotary magnet over the path; ground, contact 41, contact 30, contact 21, contact 58, winding of the electro magnet 59 to battery. By the contact 37, ground is placed on the test wiper 10 in series with the winding of relay 16 in passing by the contact 25. At contact 36, ground is connected to test wiper 13 by way of the contact 18 and the winding of relay 24. If the wipers of the finder switch are not on the set of contacts of the calling line, neither one of the relays 16 or 24 is energized and the rotary magnet is energized over the aforementioned circuit. Near the end of its stroke, the armature 58 opens the circuit of rotary magnet 59 and when the armature 58 is retracted by its spring, the wipers will be advanced into engagement with the next set of bank contacts. This operation is repeated until one of the test wipers encounters a test contact connected to battery in series with a low resistance which is the condition of a calling line. Supposing that the test wiper 10 is on the test contact of the calling line, relays 5 and 16 energize in series over the circuit, ground contact 37, contact 25, winding of relay 16, test wiper 10, test contact of the line finders bank, contact 3, the low resistance winding of relay 5 to battery. The cut off relay 5 opens the circuit of relay 2 at contact 7, removes the ground from the calling line at contact 6, and at the front contact of armature 8, establishes its holding circuit, with its two windings in series. The second winding of relay 5 is of high enough resistance to prevent the energization of the stop relay such as 16 or 24 of another finder switch and consequently to prevent another finder switch to stop on the same line.

When the relay 16 energizes, it opens the circuit of the rotary magnet 59 at contact 21 and the wipers are stopped on the set of contacts of the calling line. Furthermore, the relay 16 prepares its holding circuit at contact 17, opens the circuit of relay 24 at contact 18 and at contacts 22 and 23 connects the line wipers 11 and 12 to the contacts 50 and 52.

At the same time that the finder switch K₁ starts its line hunting movement, the preselector K₂ starts hunting for an idle hundred selector. When the relay 33 energizes as has been explained, it closes the circuit of the rotary magnet 57 by the following path: ground, contacts 43, 38, 56, winding of the magnet 57, contact 119 to battery. At the same time at contact 40 the low resistance winding of relay 42 is connected to the test wiper 53. The rotary magnet 57 operates as has been explained for the rotary magnet 59 to advance the wipers 53 to 55 inclusive. When the wipers encounter the contacts of an idle hundreds selector, such as the selector D Fig. 2 which is identified by battery on the test wire, the relay 42 is energized over the circuit: battery, winding of the magnet 98 of the control switch C₁, the first contacts of the two rows of contacts of the control switch, which are connected together by the wiper 100, contacts 80, 71, test contact of the bank of the preselector, test wiper 53, contact 40, upper winding of relay 42, to ground. Relay 42 on energizing, opens the circuit of the magnet 57 at contact 43 and the wipers are stopped on the idle hundreds selector. Furthermore, at contact 47, the lower high resistance winding of relay 42 is connected to the test wiper and at contacts 49 and 51, the calling line is extended to the relay 65 of the selector by way of the wipers 54 and 55 and the contacts 112 and 114. Relay 65 is energized in series with the calling line and by the contact 66 closes the circuit of relay 68 to ground at contact 64. On energizing relay 68 replaces the battery potential on the test wire at contact 71 by ground at contact 72, to complete the holding circuit of relay 42 in the preselector and to busy the hundreds selector to the other preselectors.

Returning now to the finder switch and the preselector. As explained the said switch and preselector begin their operation at the same time. If the preselector finds an idle hundreds selector before the finder switch has found the calling line, the circuit as described for the relay 33 is opened at contact 45 when relay 42 is energized but is immediately reestablished by the contacts 46, 35, 28, 19 and the winding of relay 33. The relay 33 being a slow relay does not fall back during the time that its circuit is open when relay 42 operates. When the finder switch finds the calling line, one of the relays 16 or 24 is energized and opens the

circuit of the relay 33 at either the contact 19 or the contact 28 and after an instance the slow relay 33 falls back.

On the other hand, if the finder switch 5 connects with the calling line before the pre-selectors finds an idle hundreds selector, if there are no other lines of the group in the calling position, when the relay 2 falls back at the energization of relay 5, ground will 10 be removed from the starting wire. But at the same time, the calling line has been extended to the contacts 50 and 52 by one of the stop relays 16 and 24 and the relay 33 remains energized in series with the calling 15 line until the relay 42 operates. In any case, the relay 33 does not fall back until the calling line is extended to an idle hundreds selector.

As a further result of the energization of 20 relay 42, ground is placed on relay 5 by the circuit, ground, contacts 44, 26, 17, winding of relay 16, test wiper 10, test contact front contact of armature 8 and the said armature, and the two windings of relay 5 to battery.

25 Relays 5 and 16 remain energized over this circuit, when relay 33 falls back and opens the contact 37. At the contact 45 the circuit of relay 33 is opened and the starting wire is extended to the contact 35, but this has 30 no effect at this time as relay 16 is energized and the contact 19 open. An instant after its circuit is open, relay 33 falls back and the starting wire is extended to the next finder switch by the contact 34.

35 In the hundreds selector as a further result of the energization of relay 68, by the contact 75, ground is placed on the contacts 2, 4, 6, 8 and 10 of the first row of bank contacts of the control switch C_1 , and on the 40 contacts 3, 5, 7, 9 and 11 of the same row of contacts in series with the upper winding of relay 90. At contact 73, relay 68 prepares the impulse circuit for the magnet 98 of the control switch, at contacts 70 and 76 45 prepares the circuit of the magnet 115 and opens at contacts 69 and 74 the release circuits of the control switch C_1 and the rotary switch K_3 .

50 When the calling line is extended to the hundreds selector, the subscriber hears a special tone induced in the induction coil 109 that indicates that he can begin to dial his number.

55 The calling subscriber will now operate his calling device dial in accordance with the first digit 9 of the called number as a result of which nine interruptions will be produced in the circuit of his line and the line relay 65 of the selector D will be deenergized 60 nine times. At each deenergization, the relay 65 transmits an impulse of current to the magnet 98 of the control switch over a path which extends from ground by way of contacts 64, 67, the winding of relay 77, contact 73, the first contact in the first row of 65 rotary switch K_3 that occupies the same po-

contacts in the bank of the control switch, the wiper 100, the first contact in the second row of contacts in the bank of the control switch, the winding of magnet 98 to battery. By the operation of the magnet 98, 70 responsive to these impulses, the wiper 100 is advanced step by step and is brought to rest on the tenth contact of the bank. Relay 77 is energized in series with the magnet 98 and since it is slow acting, it holds its 75 armature attracted during the series of impulses. Also the relay 68, on account of its slow action does not fall back during the impulses. After the first impulse, the wiper 100 leaves its normal position and the circuit of the magnet 98 is opened at this point but a new circuit for the eight succeeding impulses has already been established by the relay 77 at the contact 81. At the contact 80 79, relay 77 short circuits the upper winding of relay 90 and at contact 82 opens a point in the automatic trunk hunting circuit of the magnet 115.

When the wiper 100 comes to rest on the tenth contact of its bank, ground is placed 90 on the control wire that is connected to the control contacts in the bank of the rotary switch K_3 that occupies the same positions as the trunk lines to the line selectors of the 95 9 and 0 hundreds.

After the first step of the control switch the off normal springs are shifted and a circuit is completed for the magnet 115 to ground by the contacts 64, 106, 70, 89, 76, 83, 116 the winding of the magnet 115 to battery. As the control wiper 125 of the rotary switch K_3 , when in normal position, is on a contact connected to the second and third contacts in the second row of contacts of the 100 control switch's bank (see Fig. 5) and since the wiper 100 places ground on these contacts as it passes them, after the first impulse relay 84 is energized before the magnet 115 has time to operate, over the circuit, ground, contact 75, 2nd. contact of the first row of contacts wiper 100, 2nd. contact of the 105 2nd. row of contacts in the bank of the control switch, the control wire 101, the first contact of the 1st. group (not shown) of control contacts in the bank of the rotary switch K_3 the control wiper 125, winding of relay 84 to battery. Relay 84 opens the circuit 110 of the magnet 115 at the contact 89 before it has time to operate. After the 2nd. impulse 115 the wiper 100 places ground in series with the upper winding of relay 90 on the same control wire as for the 1st. impulse but this winding is short circuited by relay 77, so no circuit changes takes place and relay 84 remains energized. After the 3rd. impulse, 120 the wiper 100 removes the ground from the control wire 101 and places it on the control wire 102. This control wire is connected to the contacts on the control bank of the 125

130 rotary switch K_3 that occupies the same po-

sition as the trunks to the 3rd. and 4th. hundreds. When the ground is removed from the wire 101, relay 84 falls back and at contact 89 closes the circuit of the magnet 115. 5 This magnet operates in the same way as the magnets of the finder and preselector to advance the wipers 125 to 131 inclusive. The operation of the magnet 115 continues until the wiper 125 finds a grounded contact. 10 which causes relay 84 to operate again and opens the circuit of the magnet 115 at contact 89. As the advancement of the wipers begins during the impulses and that for each two impulses received by the control switch 15 C_1 the magnet 115 only advances, its wipers ten contacts, the wipers 125 to 131 inclusive are brought to rest in a very short time after the ninth impulse on the contacts of the first trunk connected to the ninth and zero 20 hundreds. An instant after the ninth impulse relay 77 falls back and when the relay 84 energizes to stop the wipers on the 9th. group of trunks, the circuits of the automatic trunk hunting operation are completed. 25 With relay 77 at rest and relay 84 energized, ground is connected to the test wiper 129 in series with the lower winding of relay 61 by way of the path, ground, contacts 78, 87, lower winding of relay 61, contacts 91 and test wiper 129. At the same 30 time, ground is placed on the magnet 115 by the circuit: ground, contacts 64, 82, 88, 76, 83, 116 the winding of the magnet 115, to battery. If the first set of contacts in 35 the 9th. group is busy there will not be a battery potential on the test contact and the relay 61 will not be energized and the magnet 115 advances the wipers in the same manner as when hunting for the group of 40 trunks. When the wipers are on an idle set of contacts, the test wiper 129 will find battery and the relay 61 is energized by the circuit; ground, contacts 78, 87, lower winding of relay 61, contact 91, test wiper 129, 45 test contact, test conductor 134, resistance 204 (Fig. 3) to battery. The circuit of the magnet 115 is opened at contact 64 and the wipers brought to rest on the contacts of an idle line selector in the 9th. hundred. As 50 a further result of the energization of the relay 61, the upper winding of relay 61 is connected at contact 62 to the test conductor; at contact 63 ground is placed on the test conductor of the preselector and at the 55 contacts 112 and 114 the circuit of the line relay 65 is opened and by the contacts 111 and 113 the line is extended to the relay 145 of the line selector (Fig. 3) by way of the contacts 95 and 97, the wipers 130 and 131 60 and the conductors 132 and 133.

The relay 145 energizes in series with the calling line and closes a circuit for the slow acting relay 153 to ground by way of the contacts 146 and 182. Relay 153 on energizing, causes a considerable number of circuit

changes. At contacts 155 battery is removed from the test conductor and ground is placed on the same to complete the holding circuit of relay 61 in the hundreds selector and to busy the line selector to all other hundreds 70 selectors. Returning now to the hundreds selector, when the relay 65 falls back, it opens the circuit of relay 68, which on account of its slow action does not fall back but an instant later in order that the holding circuit furnished by relay 153 of the line selector is assured before the contacts 72 and 75 are opened. When the contact 75 is opened, relay 84 falls back and opens the circuit of the lower winding of relay 61, 80 but this relay now has a holding circuit by the high resistance winding, the contact 62 and the grounded test conductor.

Should all of the line selectors in the 9th. hundred be busy, the magnet 115 would drive the wipers 125 to 131 inclusive on the first contact of the following group of trunks and as on this group of trunks the control contacts are not grounded, relay 84 would fall back permitting the magnet 115 to drive the wipers to their normal position. In this position, the contact 117 is opened and the circuit of the magnet 115 is opened as relay 77 has fallen back. In this position, the calling subscriber would receive the busy signal induced on the induction coil 110, as the ground for the line relay is fed through this coil by way of the contacts 85 and 107. When the calling subscriber hangs up his receiver, the release would take place 100 as will be described further on.

Returning now to the line selector, the relay 153 besides placing ground on the test conductor 134, as already explained, prepares the impulse circuits of the control switches C_2 and C_3 at contact 157; the ground at contact 159 is extended to the relay 161 by way of the wiper 207 and the first contacts in the two rows of contacts of the tens control switch C_2 ; by way of contacts 159 and 186, ground is placed on the first row of contacts of the control switch C_3 and by the wiper 214 and the first contact of the second row of contacts of the said bank, the ground is extended directly to the contacts 2, 4, 6, 8 and 10 of the first row of contacts of the tens control switch C_2 and in series with the lower winding of relay 196 to the contacts 3, 5, 7, 9 and 11 of the same row of contacts. When the relay 161 energizes, it connects at the contact 163 the impulse circuit to the magnet 205 of the tens control switch and prepares its holding circuit at contact 164.

The calling subscriber now operates the dial of his calling device in accordance with the second figure 0 of the called number, as a result ten interruptions will be produced in the circuit of his line and relay 145 will be deenergized 10 times. At each deenergi-

zation an impulse of current will be sent to the magnet 205 over a circuit which extends from ground by way of contacts 182, 147, the winding of slow relay 148, contacts 157, 170, 163 and the winding of the magnet 205 to battery. For each impulse, the magnet 205 advances its wiper 207 one contact and at the end of the ten impulses, the wiper 207 will come to rest on the 11th. contact of its bank with the result that ground in series with the lower winding of relay 196 is placed on the control conductor 222 which is connected to the control contacts of the 9th. and 10th. tens groups of lines in the bank of the rotary switch K_4 . Relay 148 is energized in series with the magnet 205 and since it is slow acting it holds its armature attracted during the train of impulses. After the first impulse the wiper 207 leaves its normal position and the first circuit of the relay 161 is opened but a second circuit is established by way of the contacts 164, 150, 186 and 159 to ground. At contact 151 relay 148 short circuits the lower winding of relay 196. Contact 209 is closed after the first step of the magnet 205 and a circuit is completed for the magnet 215 to ground by the contacts 216, 179, 209, 186 and 159. As the control wiper 224 of the rotary switch K_4 , when in normal position, is on a contact connected to the 2nd. and 3rd. contacts of the second row of contacts of the control switch C_2 (see Figure 7) and since the wiper 207 places ground on these contacts as it passes them, after the first impulse, relay 177 is energized before the magnet 115 has time to operate and opens the circuit of the said magnet at contact 179. After the third impulse the ground on the 2nd. and 3rd. contacts of the second row of contacts of the control switch C_2 is removed and the relay 177 in falling back permits the magnet 215 to operate in the same manner as the magnet 115 of the hundreds selector, and to advance the wipers 224 to 230 step by step. When the control wiper 224 reaches a grounded contact the relay 177 is energized and opens the circuit of the magnet 215, at contact 179. On account of the high speed of operation of the magnet 215, and that for each two impulses received by the control switch C_2 the magnet 215 only advances its wipers ten contacts, and that the advancement of the wipers begins during the impulses, the wipers 224 to 230 inclusive are brought to rest in a very short time after the 10th. impulse on the first line in the 9th. and 10th. tens groups of lines. An instant after the last impulse slow relay 148 falls back and removes the short circuit on the lower winding of the relay 196. This relay now energizes in series with the relay 177 over the circuit, ground, contacts 159, 186, first contact of the first row of contacts in the bank of control switch C_3 , the wiper 214 the second contact in the

first row of contacts of the said bank, the lower winding of relay 196, the 11th. contact of the first row of contacts, the wipers 207, the 11th. contact of the second row of contacts of the control switch C_2 , the first contact in the 5th. group of tens contacts in the row of control contacts in the bank of K_4 , the control wiper 224, the winding of relay 177 to battery. The relay 196 connects up the wipers 225 to 227 inclusive as they have access to the even numbered groups of ten lines, and at contact 199 closes its holding circuit to ground by way of contact 159. When the relay 148 falls back it opens the holding circuit of relay 161 at contact 150 and relay 161 falls back also. In falling back relay 161 closes the impulse circuit to the magnet 210 of the unit control switch C_3 by way of the contact 162. The calling subscriber will now operate the dial of his calling device in accordance with the last digit 3 of the called number, as a result of which three interruptions will be produced in the calling subscriber's line circuit and the line relay 145 will be deenergized three times. At each deenergization relay 145 transmits an impulse of current to the magnet 210 of the units control switch over a path which extends from ground by way of contacts 182, 147, winding of relay 148, contacts 157, 170, 162, the winding of the magnet 210 to battery. For each impulse, the magnet 210 advances its wiper 214 one contact and at the end of the three impulses the wiper 214 will come to rest on the fourth contact of its bank, with the result that ground is placed on the control conductor 223, multiplied on the 3rd. contact in each of the ten groups of control contacts of the bank of the rotary switch K_4 (see Fig. 7).

As long as the wiper 214 is in contact with the first or second contact of its bank, relay 177 remains energized but when it leaves the second contact, relay 177 falls back and closes the circuit of the magnet 215. Magnet 215 operates to advance the wipers, until the wiper 224 finds a grounded contact, in this case the third contact in the tenth group of ten lines. Relay 177 is reenergized, opens the circuit of magnet 215 at contact 179 and the wipers come to rest on the third line of the tenth tens group of lines. After the first impulse the off normal springs of the control switch C_3 are shifted and the contacts 212, 213 are closed. When the relay 148 falls back after the last impulse, the circuit of relay 169 is closed by the path, ground, contacts 159, 186, 149, 180, 213, the upper winding of 169 to battery. Relay 169 establishes its holding circuit to ground by way of contacts 159, 186, 172, the upper winding of relay 169 to battery. By the contact 171 this same ground is connected to armature 164. At contact 174 relays 161

and 189 are connected in series and by the contact 175, the test wiper 225 is connected at a point midway between the windings of relays 161 and 189, by way of the path, test 5 wiper 225, contacts 198, 185, 167 and 175. At contact 170 the impulse circuit is opened. If the called subscriber is busy, the test contact is grounded, and this ground on the test wiper 225 short circuits relay 189 and 10 energizes relay 161. As a result, of the energization of relay 161, a locking circuit is established at contact 164 (this contact is adjusted to make before the others are operated) at contact 165, the connection of 15 the test wiper to relay 161 is opened; at contact 167 the connection of the test wiper 225 to the relay 189 is opened and at the contact 166 ground is placed on the magnet by way of the circuit: ground, contacts 159, 186, 20 172, 166, 217, 216 and the winding of magnet 215 to battery. The magnet 215 operates and drives the wipers 224 to 230 inclusive to their normal position. At normal position the off normal contact 217 is opened and the 25 magnet 215 comes to rest. As a further result of the energization of relay 161, a busy signal is placed on the calling line in series with the condenser 142, by the contacts 168 and 176 to inform the calling subscriber that 30 the called line is busy and that the connection cannot be completed. The calling subscriber on restoring the receiver causes the connection to be released as will be explained further on. If the called line is idle when 35 the wipers come to rest, the test wiper will find battery on the test contact in series with the right winding of the cut off relay 234 of the called line. This winding is of low resistance and practically short circuits 40 relay 161 when relay 169 is energized. As a result, relay 189 is energized by its two windings in series but it only has enough ampere-turns to close the contact 187 without operating the others and on account of 45 the resistance of these two windings the cut off relay is not energized. At contact 187, the test wiper 225 is connected to the upper low resistance winding of relay 189 and the relays 189 and 234 are completely energized. 50 Relay 234 removes the line line relay 232 from the line at contact 237, at contact 238 removes the ground from the called line and at contact 236 removes the short circuit from around its left winding. The relay 234 remains 55 energized with its two windings in series. Returning to relay 189, a considerable number of circuit changes takes place when it is energized. At contact 188, the connection of the test wiper 225 to relay 60 161 is opened; at contact 186 the ground is removed from the holding circuits of relays 169 and 177 and by the contacts 194 and 195 it connects up the line wipers 226 and 227 to the contacts 191 and 193 of the 65 ring cut off relay 181. Relay 177, on fall-

ing back, closed the circuit of the ringing current on to the called line at contact 178 and the called subscriber's bell is rung over the circuit: ground, the ringing generator 70 221, the ringing interrupter 220, 219, contacts 178, 193, 195, 202, the wiper 227, the line conductor 233, the subscriber's bell 243 and the condenser, 242 line conductor 232, line wiper 226, contacts 200, 194, 191, the lower winding of relay 181 to battery. A 75 small capacity condenser is bridged across the contact 190 to permit a small part of the ringing current to pass out on the calling line each time that the called subscriber is rung. The slow relay 181 is not energized 80 by the ringing current, but when the called subscriber answers, a path for direct current is completed at the called subscriber's station in series with the transmitter and receiver and the relay 181 is energized. As a result 85 of the energization of relay 181, a holding circuit is established at contact 184; at contacts 190 and 192, the calling line is extended to the battery feed relay 135. Relay 135 energizes in series with the called line 90 and the called subscriber's station. As a result of the energization of relay 135, the battery to the calling line is reversed at the contacts 140—141 and 138—139 for supervisory purposes. As a further result of the 95 energization of relay 181, the ground on the winding of relay 153 is opened at contact 182 but is immediately reestablished by the contact 186, when relay 135 is energized. The two subscribers are now in communication 100 and the circuit of the voice currents is shown by the heavy lines.

At the end of the conversation, when either the called or the calling subscriber replaces his receiver, the relay 153 falls back. 105 If the calling subscriber replaces his receiver first, the relay 145 in falling back opens the circuit of relay 153 at contact 146 and, if it is the called subscriber who hangs up his receiver first, the relay 185 falls back 110 and removes the ground on the winding of relay 153 at contact 136. Relay 153 in falling back removes the ground on the test conductor 134 and relay 61 of the hundred's selector, Fig. 2, is deenergized, and in falling back the connection of the calling line to relay 145 of the line selector is opened at contacts 111 and 113, and relay 145 falls back. As another result of the deenergization 115 of relay 153 contact 159 opens and removes the ground from the holding circuits of relays 181, 189 and 196. When relay 189 restores the wipers are disconnected at contacts 194 and 195. When relay 181 falls back, ground is connected to the magnet 215 120 over the circuit; ground, contacts 182, 147, the winding of relay 148, contacts 158, 217, 216, the winding of magnet 215 to battery. Magnet 215 operates and drives the wiper 224 to 230 inclusive to their normal pos. 125 130

tion. In this position contact 217 is opened and the wipers are brought to rest.

As another result of the deenergization of relay 153 at contact 154, ground is placed on 5 the magnet 205 of the control switch C_2 and at contact 160 the circuit of magnet 210 of the control switch C_3 is closed. Magnet 205 operates to drive wiper 207 to normal position. In this position, the off normal 10 springs are shifted; contact 205 is opened and wiper 207 comes to rest. In a similar manner, magnet 210 drives the wiper 214 to normal position and the circuit of the magnet 210 is opened at contact 212.

15 During the operation of the magnet 215, relay 148 is energized and opens the test conductor at contact 152 thus causing the test line selector to test busy until the wipers are in normal position. An instant after 20 the contact 217 is opened, relay 148 falls back and the line selector is in position to receive another call.

In the hundred's selector, when relay 61 falls back the ground is removed from 25 the test conductor leading to the preselector, and from the holding circuit of relay 90 at contact 63, and at contact 64, the circuit of magnet 115 is closed to ground by the path, ground contacts 64, 67 winding 30 of relay 77, contacts 74, 117, 116, the winding of magnet 115 to battery. Magnet 115 operates to drive the wipers 125 to 131 inclusive to their normal position. In the normal position contact 117 is opened and 35 the wipers come to rest. Relay 77 energizes during the operation of the magnet 105, and opens at contact 80 the test conductor leading to the bank contacts of the preselectors, thus causing the hundreds selector to test busy until the wipers are in 40 normal position. At the same time that ground is placed on magnet 115, the circuit of the magnet 98 is closed by the path, ground, contacts 64, 106, 69, 99 and the 45 winding of the magnet 98 to battery. The magnet 98 operates and drives the wiper 100 to its normal position. In this position, the off normal springs are shifted contact 106 is opened, and the wiper 100 comes to rest. In normal position, the wiper 100 50 connects battery to the test conductor and when the relay 77 falls back after the operation of magnet 115, the hundreds selector is in position to be taken for another 55 call.

In the preselector, when ground is removed from the test conductor, the relay 42 falls back, and the wipers 53 to 55 inclusive, having no normal position, remain on the 60 contacts of the selector last used. As a result of the deenergization of relay 42, ground is removed from the cut off relay 5 of the calling line in series with relay 16 and relays 5 and 16 fall back. As the 65 wipers 10 to 15 inclusive of the finder

switch have no normal position they remain on the contacts of the line last connected. When the calling line cut off relay 5 falls back the line relay is again connected to the line and the calling line is free to receive or 70 initiate another call.

The operation of the system having been described when the call is for a subscriber with only one line, its operation when the call is for a subscriber having several lines 75 listed under one number will be explained. For this purpose, it will be assumed that the subscriber at station P desires to establish a connection with the subscriber whose telephone number is 016 and that this 80 subscriber has three lines.

When the receiver is removed at station P the calling line is extended to a hundred's selector as explained in the previous case, assuming that the selector D (Fig. 2) is again used for the connection, when the calling subscriber operates his dial in accordance with the first digit 0 of the desired number, ten interruptions will be produced in his line circuit and the line relay 65 will send ten impulses of current to the magnet 98 and the wiper 100 will come to rest on the 11th. contact of its bank, the selector will operate as previously explained with the exception that, since the wiper 95 100 is on the 11th. contact of the control switches' bank, relay 90 will energize in series with relay 84 when the relay 77 falls back after the last impulse over the circuit; ground, contact 75 the upper winding of relay 90, 11th. contact of the first row of contacts, wiper 100, 11th. contact of the second row of contacts of the control switch C_1 , control conductor 105, 1st. contact of the 5th. group of control contacts 105 in the bank of K_3 , control wiper 125, the winding of relay 84 to battery. At contact 93, relay 90 establishes its holding circuit by its lower winding to ground at contact 72 and at contact 63 when relay 61 is energized.

The wipers 126 to 128 inclusive are connected up at contacts 92, 94 and 96 and will be used in establishing the connection. The selector proceeds to hunt an idle line selector as previously explained and will extend the calling line to the same when it is found. Assume that the line selector F (Fig. 4) is used for the connection.

When the relay 61 of the hundred's selector extends the lines to F (Fig. 4) relay 258 energizes in series with the calling line and at contact 259 closes ground, on to relay 266. Relay 266 on energizing disconnects the battery from the test conductor at contact 268 and places ground on the same at contact 269. Another result of the energization of relay 266, the impulse circuit is prepared at contact 270. As a further result of the energization of relay 266, ground 125 130

is placed on the first row of contacts of the control switch C'_3 and on the 2nd, 4th, 6th, 8th and 10th. of the first row contacts of control switch C'_2 , by way of the contacts 272 and 312.

By way of the 1st. contact in row 1, wiper 335, 1st. contact in row 2 of the control switch C'_3 , upper winding 318 the same ground is placed on the 3rd, 5th, 7th, 9th, 10 and 11th, contacts of the first row of contacts of the same control switch C'_2 . Furthermore, the circuit of relay 274 is closed to ground by the path, ground, contact 272, the 1st. contact of the 1st row, wiper 328, 15 the 1st. contact of the 2nd. row of control switch C'_2 , the upper winding of relay 274 to battery. As a result of the energization of relay 274, the impulse circuit is connected to magnet 326 at contact 276 and at contact 20 277 a holding circuit for relay 274 is prepared.

The calling subscriber will now operate his calling device in accordance with the second digit 1 of the desired number, as a result of which, four interruptions will be produced in the circuit of his line, and the line relay 258 of the line selector F will be deenergized once, and one impulse of current will be sent to the magnet 326 over 25 the circuit, ground, contacts 302, 260, the winding of relay 261, contacts 270, 315, 283, 276, the winding of magnet 326 to battery. The magnet 326 operates and advances the wiper 328 on to the 2nd. contact of the bank. Relay 261 energizes in series with the magnet 326 and at contact 263 completes the holding circuit of relay 274, and at contact 264 short circuits the upper winding of relay 318. This latter operation 30 has no effect in this case as the wiper 328 is at rest on the 2nd. contact of its bank, and ground is placed on the 1st. control contact of the first tens group of contacts in the bank of the selector switch, and since 35 the control wiper 338, in normal position rests on this contact, the relay 289 is immediately energized and opens the circuit of the magnet 346 at contact 292 before it has time to operate, by the ground that is placed on its circuit at contact 330 after 40 the first step of the magnet 326. An instant after the impulse of current, relay 261 falls back, causing the deenergization of relay 274. Relay 274 on falling back 45 closed the impulse circuit to the magnet 331 of the control switch C'_2 .

The calling subscriber will now operate his calling device in accordance with the last digit 6 of the desired number and as a result of which 6 interruptions will be produced in the circuit of his line and the line relay 258 will be deenergized 6 times. At each deenergization, the line relay 258 transmits an impulse of current to the magnet 331 over a path which extends from

ground by way of contacts 302, 260, winding of relay 261, contacts 270, 315, 283, 275, the winding of magnet 331 to battery. By the operation of the magnet 331, responsive to these impulses, the wiper 335 is advanced to the 7th. contact of its bank and places a ground on the 6th. control contact in each group of tens contacts in the bank of the selector switch. When the wiper 328 leaves the 3rd. contact of its bank the circuit of relay 289 is open, and relay 289 on falling back, closes the circuit of the magnet 346 at contact 292 and the magnet 346 operates and advances the wipers 338 to 344 inclusive. When the wiper 338 finds a grounded contact, which in this case, is the 6th. contact in the first group of ten lines, the relay 289 is reenergized and opens the circuit of the magnet 346 and the wipers 338 to 344 inclusive come to rest on the first line of the three lines having the same telephone number, in this case the 016. After the first step of the magnet 331, the contact 334 is closed and when relay 289 is energized after the last train of impulses, it closes the circuit of relay 282 over a path extending from ground by the contacts 272, 312, 262, 290, 284, the upper winding of relay 282 to battery. Relay 282 on energizing, establishes its holding circuit at contact 285, to ground by way of the contacts 312 and 262. As a result of the energization of relay 282, the impulse circuit is opened at contact 283: at contact 284, ground for the holding circuit of relay 274 is connected and by contacts 279, and 305, this ground is extended to the lower winding of relay 289 and to the relays 294 and 297 in series by way of contact 348. At the same time, the test wiper is connected to a point between the windings of relays 294 and 297, by the path, the test wiper 342, contacts 319, 313, 291, 286 and one side of the winding of relay 294. If the first line of the three lines is busy, there is ground on the test contact in series with a relay such as relay 16 or 24 of the finder switch (Fig. 2), if the line is calling or in series with a resistance such as resistance 363 if the line is busy by being called. In either case, relay 294 is shunted by this resistance to such an extent that it is not energized when the test wiper is on the contact of a line having a resistance such as 360 and 361 connected in series with the winding of the cut off relay. Relay 297 energizes by the ground on the test contact in series with the resistance such as 363 or the relay such as 16 or 24 (Fig. 2). As a result, ground is connected to the magnet 346 over the path ground, contacts 272, 312, 296, 300, the winding of the magnet 346 to battery. The magnet is energized and at contact 348, disconnects the test wiper 342 from the winding of relay 297. Relay 297 on deenergizing opens the circuit

of the magnet 346 at contact 300, and the magnet 346 on retracting its armature advances the wipers 338 to 344 inclusive on to the contact of the next line. When the control wiper leaves the 6th. contact of the group of ten lines, the circuit of the upper winding of relay 289 is opened but it is held energized by the lower winding over the circuit already described. If the second line is busy the same operation is repeated and the wipers are advanced to the third and last line of the group. On this line, the test conductor is connected directly to the winding of the cut off relay and the resistance 362, similar to the resistances 360 and 361, is excluded from the circuit. If the last line is busy, there is enough current through the winding of relay 294, on account of the comparatively low resistance of the winding of the cut off relay 359, to cause the relay 294 to operate at the same time that relay 297 operates. As a result of the energization of relays 294 and 297, the circuit of relay 274 is closed over the path, ground, contacts 272, 312, 295, 298, lower winding of relay 274 to battery. As a result of the energization of relay 274, a locking circuit is established at contact 278; at contact 279, the ground extending to relays 289, 294 and 297 is removed; at contact 281, the busy signal is placed on the calling line, in series with the condenser 257. As a further result of the energization of relay 274, a circuit for the magnet 346 is established at contact 280 by the path extending from ground by way of contacts 272, 312, 284, 280, 249, 347, the winding of magnet 346 to battery. The magnet 346 operates and drives the wipers 338 to 344 to their normal position. In this position, contact 349 is opened and the wipers come to rest. The calling subscriber on hearing the busy signal will hang up his receiver and the release takes place as will be described further on.

Assuming now that the first line of the group of three lines is idle, when the wipers are brought to rest on the contacts of the line, test wiper finds battery in series with the right low resistance winding of relay 357, and the relay 297 shunted by the battery in series with the low resistance winding of relay 357 is not energized but relay 294 is energized over the circuit, ground contacts 272, 312, 284, 279, 305, winding of relay 294, contacts 286, 291, 313, 319, test wiper 342, test wire 354 and the right hand winding of relay 357. As a result of the energization of relay 294, the circuit of relay 310 is closed by a path extending from ground, contacts 272, 312, 295, 299, the winding of relay 310 to battery. Relay 310 energizes and at contact 311 establishes a locking circuit to ground by way of contact 272. As a further result of the energization of relay 310, ground is removed from the banks of the control switches C₂ and C₃, and from the contacts 284, 285 and 295. Relays 282, 294 and 297 fall back. As another result of the energization of relay 310, ground is placed on the winding of the cut off relay 357 over the path, ground, resistance 363, contacts 314, 319, test wiper 342, test wire 354 and the right hand winding of relay 357 to battery. Relay 357 energizes in series with the resistance 363 and 70 replaces its left hand winding and the resistance 360 in series with the right hand winding. Furthermore, the relay 357 removes the line relay (not shown) from the called line. 80

Furthermore, at the energization of relay 310, the connection of the test wiper to the relay 294 is opened at contact 313; the impulse circuit is opened at contact 315 and the line wipers extended to the contacts 307 85 and 309 of the ring cut off relay 301 at contacts 316 and 317. 90

The ringing of the called station (not shown) and the conversation proceed, as explained for the normal line selector, and the release of the connection takes place in the same general way, when either of the subscribers hangs up his receiver. Relay 266 falls back, if the called subscriber hangs up first, relay 248 in falling back removes the ground on relay 266 at contact 249 and if the calling subscriber hangs up his receiver first, the relay 256 falls back and opens the circuit of relay 266 at contact 259. Relay 266 on falling back, removes the ground on test conductor 247 at contact 269 and relay 61 in the hundred's selector D (Fig. 2) falls back and disconnects the line conductor at contacts 111 and 113. As a further result of the deenergization of relay 266, ground is placed on the magnet 326 of the control switch C₂ by a path extending from ground by contacts 267, 329, the winding of magnet 326 to battery. Magnet 326 operates and drives wiper 328 to the normal position. In this position, the contact 329 is opened and the wiper 328 is brought to rest. By contact 273, ground is placed on the magnet 331 of the control switch C₃, in series with the contact 333. Magnet 331 drives the wiper 335 to normal position and in this position, the circuit of the magnet 331 is opened at contact 333 and the wiper is brought to rest. As another result of the deenergization of relay 266, ground is removed from the holding circuits of relays 301 and 310 at contact 272 and these two relays fall back. Relay 310 on falling back, disconnects ground from the test wiper at 314 and disconnects the line wipers at 316 and 317. The removal of ground from the test wiper 342 causes the cut off relay 357 to fall back and the called line is free to initiate or receive another call. As a result of the deenergization of relay 310, ground is removed from 100

110

115

120

125

130

tion of relay 301, a circuit is closed for the magnet 346 which may be traced from ground, contacts 302, 260, winding of relay 261, contacts 271, 349, 347, the winding of 5 magnet 346 to battery. Magnet 346 operates in series with the relay 261 and drives the wipers 338 to 344 to their normal position. In the normal position contact 349 is opened and the wipers come to rest. 10 During the operation of magnet 346, relay 261 remains energized and the connection of the test conductor to battery is opened at contact 265. As a result of which the line connector is busied to any further calls 15 An instant after, the magnet 346 ceases to operate relay 261 falls back and the line selector may be seized for another call.

The release of the hundred's selector, pre-selector, finder switch and the cut off relay 20 of the calling line is effected as previously described and need not be repeated.

When all the hundreds selectors of a group of preselectors are busy, the group of preselectors are marked Busy. Referring 25 now to Fig. 2, there is shown for each selector a chain relay such as 118, 118', and 118'', which is energized as soon as the selector is taken. When all the selectors of a group are engaged, all the chain relays of 30 the group are energized, and the circuit of the busying relay 120 is closed. This relay on pulling up, places ground instead of main battery on the magnets of the pre-selectors. As a result of the changing of the 35 polarity of the magnets, the relay 42 of all the idle preselectors in the group energize over the circuit: ground, contact 121, magnet 57, contacts 56 and 39, resistance, contact 48, lower winding of relay 42 and main battery, at contact 45, the circuit of relay 33 is 40 opened, and the starting wire is switched to the following preselector, at contact 46. When a selector in the group becomes free, the corresponding chain relay falls back, 45 opening the circuit of relay 120, which on falling back makes the busied preselectors available for connections.

A traffic meter 60 is provided for the line 50 finders. When a line finder such as the line finder A finds a calling line, one of the relays 16 or 24 is energized at the same time as the relay 33 and the circuit of the meter is closed by the circuit: ground, contact 41, contact 20 (or 29), the meter 60, and main 55 battery. When the relay 33 falls back the circuit of the meter 60 is opened and it falls back after having registered a call.

Having explained the process of setting 60 up and releasing a typical connection when the circuit arrangements shown in Figs. 2, 3 and 4 are employed, it will be desirable now to consider briefly the establishment of a connection when the circuit arrangement shown in Fig. 8 is used.

65 In this case, the control switches instead

of being individual each to a certain selector, are common to a number of selectors of the same category, the number of selectors associated with each control switch depending on the traffic to be handled and the control 70 switches such as C''₁, C''₂ and C''₃ are inserted in the circuit of a selector, only during the time necessary for the operation of the selector, the other selectors which may be connected to the control switch in use 75 being busied during this time, in order that other calls may be directed to other groups of selectors which are free to receive them.

In Fig. 8, the common control switch C''₁ 80 is connected to its associated hundreds selector's circuit, one of which is represented at D' by the common conductors 434 to 442 inclusive, and the common control switches C''₂ and C''₃ connected to their associated line selector's circuit, one of which is represented at E' by the common conductors 525 to 530 inclusive.

Assuming now that the subscriber at station P desires to establish a connection with the subscriber whose telephone number is 90 733.

When the receiver is removed at station P the calling line is extended to a hundreds selector as previously explained, assuming the selector D' (Fig. 8) to be the selector 95 taken. Relay 455 is operated before the relay 33 in the preselector falls back over the following circuit: negative battery, magnet 407 of the control switch C''₁, the first set of bank contacts of C''₁, short circuited by 100 the wiper 408, in normal position, contact 419, the common conductor 437, contact 456, upper winding of relay 455, contact 472 established when the rotary switch K''₃ is in normal position, contact 459, test conductor 105 483, test contact, test wiper 53 of the preselector B, Fig. 2, contact 40, upper winding of relay 42, to ground. As a result of the energization of relay 455, the calling line is connected to relay 429 by the contacts 453 110 and 454, at contact 450 a holding circuit for the lower winding is prepared, at contact 448, ground is placed on the 2nd, 4th, 6th, 8th and 10th contacts of the first row of contacts in the bank on the control switch C''₁; 115 at contact 449, ground is placed on the 3rd, 5th, 7th, 9th and 11th contacts of the same bank in series with the lower winding of relay 464; at contact 444 the control wiper 476 is connected to the control relay 433 by way of the common conductor 442, at contact 445 an operating circuit for the magnet 475 is connected to the common operating conductor 441; at 447 a second operating circuit for the same magnet is connected 120 to a second common operating conductor 440, and at contact 451 a circuit for placing ground on the test conductor 483 is prepared.

Relay 429 energizes in series with the call- 130

ing line and by the contact 415 closes the circuit of relay 431. As a result of the energization of relay 431, battery is removed from the conductor 437 and replaced by 5 ground, at contact 418, the holding circuit for relay 455 is completed to ground by way of contacts 418, 456 and 450, and by way of contacts 451 and 459, ground is placed on test conductor 483; at contact 413, the 10 impulse circuit for the magnet 407 is prepared and at contact 412, the common operating conductor is connected to an off normal contact 405, of the control switch C''₁. Ground is extended to the upper winding 15 of relay 429 in series with the secondary winding of the induction coil 402, which has a vibratory current impressed on its primary winding, and the calling subscriber hears a special tone that indicates that he 20 may begin to operate his calling device.

The calling subscriber will now operate his calling device in accordance with the first figure 7 of the called number and as a result of which seven interruptions are produced in the circuit of his line, and the relay 429 will be deenergized seven times. At each deenergization, relay 429 transmits an impulse of current to the magnet 407 of the control switch C''₁ over a circuit which 25 extends from ground by way of the contact 416, winding of the slow relay 430, contacts 413, 414, winding of magnet 407 to battery. By the operation of the magnet 407 responsive to these impulses the wiper 408 is rotated into contact with the 8th series of contacts and places ground on the control conductor 443. Relay 430 energizes in series with the magnet 407 and remains in operated position during the series of impulses. 30 Relay 431, also remains in operated position during the impulses. After the first step of magnet 407, the off normal contacts 403 to 405 inclusive are shifted and ground is extended to the magnet 475 of the rotary switch K''₃ by way of the path, ground, contacts 405, 412, 423, 426, common conductor 441, contacts 445, 474, the winding of magnet 475 to battery. The magnet 475 operates and advances the wipers 476 to 482 35 inclusive. When the wiper 476 comes into contact with the first contact of the group to which is connected the grounded control conductor 443, relay 433 of the control switch C''₁ is energized over the circuit extending from ground by way of contact 448, wiper 408, the 8th contact in the two rows of contacts of control switch C''₁, common control conductor 443, wiper 476, contacts 444, the common conductor 442, the 40 winding of relay 433, to battery.

As a result of the energization of relay 433, the operating circuit of magnet 475 is opened at contact 426 and the wipers 476 to 482 inclusive come to rest; at contact 425, the circuit of relay 432 is closed (relay

430 restores an instant after the last impulse) by a path extending from ground by way of contacts 405, 412, 423, 425, 417, the winding of relay 432 to battery; and at contact 427 ground is connected to the test 70 wiper 480 in series with the lower winding of relay 463 over the path, ground contact 427, contact 424' common conductor 439, contact 452, the lower winding of relay 463, contact 465 and the wiper 480. 75

As a result of the energization of relay 432, the impulse circuit of magnet 407 is opened at contact 414; at contact 421, which is closed before the other contacts are actuated, a holding circuit is established by way of contacts 412 and 405 to ground and at contact 422, ground is connected to the magnet 475 over the path, ground, contacts 405, 412, 422, the common conductor 440, contacts 447, 457, 473, 474, the winding of magnet 475 to battery. If the first trunk of the group is busy, test wiper 480 is not connected to battery by the test contact and relay 463 is not energized and as a result magnet 475 operates and advances the 80 wipers 476 to 482. When the wipers are on the contacts of an idle trunk line test wiper 480 finds battery on the test contact and relay 463 is energized over the above described circuit. As a result of the energization of relay 463, numerous circuits changes are produced. At contact 458, the upper winding of relay 463 is connected to test wiper 480; at contact 457, the operating circuit of magnet 475 is opened and the wipers 476 to 90 95 100 105 110 115 120 125 130

482 come to rest on the idle trunk line; at contact 460, ground is connected to the test conductor 483; at contacts 461 and 462, the calling line is connected to the line wipers 481, 482; at contact 459, the upper winding of relay 455 is disconnected from the test conductor 483 and finally, at contact 456, the holding circuit of the lower winding of relay 455 is opened. Relay 455 being slow acting remains in its operating position long enough, after its circuit is opened, to permit the relays in the following switch to energize and establish a holding circuit for the relay 463 by its upper winding. When relay 455 falls back, the connections with the common conductors 434 to 442 are opened and as a result, relays 429 and 433 fall back. Relay 429 on restoring opens the circuit of relay 431 at contact 415 and relay 431 an instant afterwards restores. When relay 431 falls back, the circuit of the magnet 407 of the control switch C''₁ is closed to ground by way of the path, ground, contacts 405, 411, 406, winding of magnet 407 to battery. The magnet 407 operates and advances its wiper 408 to normal position. In normal position, contact 405 is opened and wiper 408 comes to rest on the first series of contacts and the control switch is free to be connected to another selector.

Since the seizure of the hundreds selector D', the other selector in the same group having access to the control switch C''₁ are busied on account of the fact that on the 5 energization of relay 431, negative battery is removed from the common conductor 437. During the time that the control switch C''₁ restores its wiper, the associated switches are busied until the wiper 408 establishes the connection between the first contact of the two row of contacts of control switch C''₁.

If all the lines of a group are busy, the wipers of the selector pass on to the contacts 15 of the first line of the following group, but there is no ground on the corresponding control contact and the relay 433 has its circuit open and falls back, preventing the energization of the relay 465, and the wipers are 20 rotated to their normal position, the electromagnet 475 being in the same circuit as previously described, which is opened at the normal position at contact 473. Moreover, the relay 433 by falling back closes at 25 428 and 424 the circuit of the secondary winding of the induction coil 409, which has a busy tone impressed upon its primary winding thus giving the busy signal to the calling line through the condenser 410.

30 Returning now to the line selector, assuming that the line selector seized by the hundreds selector D' is the line selector E', Fig. 8.

When the test wiper comes into contact 35 with the test contact connected by the test conductor 486 to battery a circuit is established, as already described, from ground, contact 427, common conductor 439, contact 452, lower winding of relay 463, contact 465, 40 wiper 480, test conductor 486, contacts 550, 583, upper winding of relay 536, contacts 544, 497, 495, resistance 492 to battery.

Relay 536 energizes in series with the relay 463 of the selector D' and there results 45 numerous circuit changes. At contacts 540 and 541, the calling line is connected to the relay 489 by way of the common conductors 525 and 526; at contact 533, the control wiper 591 is connected to the common conductor 530; at contact 534, an operating circuit for magnet 586 is connected to the common conductor 529; at contact 535 relay 546 is connected to the common conductor 527; at contact 537 a holding circuit for relay 536 is 50 prepared; at contact 538, a circuit for grounding test conductor 486 is prepared and finally, at contact 539, ground is removed from the restoring circuit of magnet 586.

60 Relay 489 energizes in series with the calling line and by the contact 490 closes the circuit of the slow relay 504 to ground. Relay 504 on energizing, removes battery from the common conductor 528 at contact 497 and all of the line selectors associated with

the control switches C''₂ and C''₃ are busied. At contact 498, relay 504 places ground on the common wire 528 to hold the relays in the preceding switches energized. As another result of the energization of relay 504 70 the impulse circuit for magnet 518 is prepared at contact 507; at contact 499, ground is placed on the first row of contacts of the control switch C''₃ and on the first row of contacts of control switch C''₂ by way of the 75 wiper 524 and the first contact of the second row of contacts of C''₃ and at contacts 505 and 506 the restoring circuit of control switches C''₂ and C''₃ are opened.

The calling subscriber will now operate 80 his calling device in accordance with the second figure 3 of the called line and as a result there will be three interruptions in his line circuit and relay 489 will be deenergized 85 three times. For each deenergization, relay 489 sends an impulse of current to magnet 518 over the circuit ground, contact 491, the winding of relay 493, contacts 507, 508, the winding of magnet 518 to battery. By the operation of the magnet 518 responsive to 90 these impulses, the wiper 519 is rotated into contact with the 4th. contact and connects ground to the tens control conductor 532. Relay 493 energizes in series with the magnet 518 and remains in operated position during 95 the series of impulses. Relay 504 also remains in operated position during the impulses. After the first step of magnet 518, ground is connected to the magnet 586 of the rotary switch K''₄ by the circuit, ground contacts 499, 515, 514, common conductor 529, contacts 534, 543, 585, the winding of magnet 586 to battery. The magnet 586 operates and advances the wipers 591 to 594 inclusive. When the wiper 591 comes into contact with the test contact connected to the control conductor 532, relay 599 is energized over the circuit, ground, contact 499, first contacts and wiper 524 of control switch C''₃, first row of contacts wiper 519, 100 4th. contact in the second row of control switch C''₂, tens control conductor 532, control wiper 591, contact 533, common conductor 530, the winding of relay 599 to battery. 105

As a result of the energization of relay 599, the operating circuit of magnet 586 is opened at contact 514 and the wipers 591 to 594 inclusive come to rest on the first line of the third group of ten lines. At contact 513, a link in the circuit of relay 546 is connected up and the circuit of relay 510 is closed at contact 512, relay 493 having fallen back an instant after the last impulse, and the relay 510 energizes over the circuit ground contacts 494, 512, the winding of relay 510 to battery. As a result of the energization of relay 510, at contact 509, the impulse circuit is connected to the magnet 523 of control switch C''₃, and at contact 511 a locking 115 circuit is established to ground by the path 120 125 130

ground, contacts 499, 511, the winding of relay 510 to battery. The subscriber will now operate his calling device in accordance with the last figure 3 of the called line and as 5 a result, there will be produced three interruptions in his line circuit. Relay 489 will deenergize three times and for each deenergization will send an impulse of current to magnet 523 of control switch C''_3 over the 10 circuit, ground contact 491, winding of slow relay 493, contacts 507, 509, the winding of magnet 523 to battery. Magnet 523 responsive to the impulses, rotates the wiper 524 on to the 4th. series of contacts and 15 places ground on the units control conductor 531. After the first step of the magnet 523, another link in the circuit of relay 546 is closed at contact 520, but this is without effect at this time as relay 493 energizes in 20 series with the magnet 523 and opens the circuit of relay 546 at contact 496. After the second impulse ground is removed from the relay 599, by the wiper 524, and relay 599 in restoring again closes the circuit of the 25 magnet 586 of the rotary switch K''_4 . Magnet 586 operates and advances the wipers 591 to 594 inclusive. When the control wiper 591 comes into contact with the control contact connected to the grounded unit's 30 control conductor 531, relay 599 energizes again, opens the circuit of magnet 586 and the wipers come to rest on the contacts of the called line.

When the relay 493 falls back after the 35 last impulse, with relay 599 operated, the circuit of relay 546 is closed over the path ground, contacts 499, 511, 520, 513, 496, 535 the winding of relay 546 to battery. Relay 546 on energizing establishes a locking circuit at contact 545 to ground by contact 562, the common conductor 528 and contact 498; at contact 543 the operating circuit of the magnet 586 is opened at contact 544, the holding circuit of relay 536 is opened; 40 at contact 542, the test wiper is connected to the relay 579; at contact 547 a holding circuit for relay 567 is prepared; at contact 548 relays 567 and 579 are connected in series, at contact 550 test conductor is disconnected from the upper winding of relay 536 and from the contact 538; at contact 549 ground is placed on the test conductor 486 and at contacts 551 and 552, the calling line is connected in series with the 45 contacts 555 and 557 to the battery feed relay 559. Relay 559 energizes in series with the calling line and closes the circuit of slow acting relay 561. Relay 561 energizing, places ground by the contact 563 on the relay 579, on the locking circuit of relay 546, and prepares the holding circuits for the 50 relays 567 and 568.

An instant after, its circuit is opened, 55 slow acting relay 536 falls back. As a result of the restoring of relay 536, the circuit of

relay 489 is opened at contacts 540 and 541; at contact 533 the circuit of relay 599 is opened.

Relay 489 falls back followed an instant later by the relay 504. When relay 504 restores, the circuit of relay 510 is opened at contact 499 and at contacts 505 and 506 the restoring circuits for the switches C''_2 and C''_3 are closed to ground in series with the winding of relay 493 and contact 491. Magnets 518 and 523 operate and advance their respective wipers 519 and 524 to normal position. At normal position, the circuit of magnet 518 is opened at contact 516, and that of magnet 523 at contact 521. During 80 the restoration of wipers 519 and 524 relay 493 is energized and removes the battery from the common conductor 528 in order to busy all of the associated line selectors while the control switches are restoring. The control switches C''_2 and C''_3 may now be employed to establish another connection.

Returning now to the line selector E', if the called line is busy, the test wiper 592 finds ground on the test contact, relay 579 90 is shunted out and relay 567 is energized over the circuit, ground, test wiper 592, contacts 565, 542, 580, 548, 570, the winding of relay 567 to battery. Relay 567 on energizing closes a locking circuit at contact 569 to ground by way of contacts 547 and 563, 95 opens the energizing circuit at contacts 570 and 565, and at contact 572 places a busy signal on the calling line by way of the path: battery, induction coil 587, contact 572, condenser 597 and the calling line. The calling subscriber on hearing the busy tone will restore his receiver and the release takes place as will be described further on.

Assuming that the called subscriber is 100 idle, in this case the test wiper 592 finds battery in series with a low resistance winding of the cut off relay such as the relay 596, the relay 567 is shunted and relay 579 is 105 energized over the circuit, battery, right hand winding of relay 596, contact 595, test wiper 592, contacts 565, 542, the two windings of relay 579 in series, contact 563, to ground. With its two windings in series relay 579 only has enough ampere turns to close the contact 578. At contact 578 the upper high resistance winding is short circuited and relays 579 and 596 are fully energized. On being fully energized the cut off relay 596 places its left hand high resistance 110 winding in series with its low resistance winding and the relay 579. Relay 579 remains in operated position when in series with the two windings of relay 596.

At contact 580, the connection between the test wiper 592 and the relay 567 is opened and at contacts 581 and 582, the line wipers 593 and 594 are connected to the ringing machine in series with the contacts 575 and 115 577.

The ringing of the called subscriber and the connection for conversation proceed as in the previously described case.

At the end of the conversation, when either subscriber restores his receiver, the circuit of the slow relay 561 is opened; at contact 553 in case that the called subscriber restores first and at contact 560 if the calling subscriber is the first to restore. The relay 561 on falling back removes the ground at contact 563 from the holding circuits of relays 546, 568 and 579, and closes the restoring circuit for the magnet 586 at contact 564, to ground by way of the path ground contacts 539, 564, 584, 585, the winding of magnet 586 to battery. The magnet 586 operates and drives the wipers 591 to 594 inclusive to the normal position. In normal position, the contact 583 is closed and 584 is opened and the wipers come to rest.

During the interval of time between the falling back of relay 546 and the instant that the wipers come to rest in normal position, the selector is busied to all other calls on account of the fact that battery is not connected to the test conductor 486 until the contact 583 is established.

The preselector and finder switch are released in the same manner as described in the previous case.

When relay 546 restores ground is removed from the test conductor 486 and the relay 463 in the hundreds selector D' falls back. On restoring relay 463 removes the ground on test conductor 483 at contact 460, at contact 457 the circuit of the magnet 475 is closed to ground by a circuit extending from ground by way of contacts 446, 457, 473, 474 the winding of magnet 475 to battery. The magnet 475 operates and drives the wipers 476 to 482 inclusive to normal position. At normal position, contact 473 is opened and the wipers come to rest.

The contact 472 being open as long as the wipers are in off normal position, the selector is busied to all other calls, after relay 463 falls back and until the wipers reach normal position on account of the fact that battery is not connected to the test conductor 483.

The object and the scope of the invention having been described, what is considered to be new and what I claim as my invention and desire to secure by Letters Patent is:

1. In an automatic telephone system, a calling line, a called line, an electrical impulse sending device, an impulse receiving organ for the said impulses, a single motion connecting mechanism for connecting calling and called lines, the said mechanism consisting of a certain number of series of contacts, and an equal number of series of wipers, means for setting the wipers in accordance with the position of the impulse

receiving organ, means for inserting a certain series of wipers in the connecting circuit according to the position of the impulse receiving organ.

2. In an automatic telephone system, a calling line, a called line, an electrical impulse sending device, an impulse receiving organ for the said impulses, a single motion connecting mechanism for connecting calling and called lines, the said mechanism consisting of a certain number of series of contacts and an equal number of series of wipers, means for setting the wipers in accordance with the position of the impulse receiving organ, contacts disposed for connecting the calling line to a certain determined series of wipers, switching relays for operating the said contacts, means for energizing certain of these relays according to the position of the impulse receiving organ.

3. In an automatic telephone system, a calling line, a called line, an electrical impulse sending device, an impulse receiving organ for the said impulses, a single motion connecting mechanism for connecting calling and called lines, the said mechanism consisting of a certain number of series of contacts and an equal number of series of wipers, means for setting the wipers in accordance with the position of the impulse receiving organ, contacts disposed for connecting the calling line to a certain determined series of wipers, switching relays for operating the said contacts, means for energizing certain of these relays according to the position of the impulse receiving organ and means for preventing the energization of the said relays until the end of a train of impulses.

4. In an automatic telephone system as claimed in claim 2 an impulse receiving organ consisting of a rotary switch having several rows of contacts, each row containing the same number of contacts, and wipers disposed for connecting electrically certain of the said contacts to certain switching relays in order to cause their energization.

5. In an automatic telephone system, a calling line, a called line, an electrical impulse sending device, an impulse receiving organ consisting of a rotary switch having several rows of contacts, each row containing the same number of contacts, and wipers; a single motion connecting mechanism for connecting calling and called lines, the said mechanism consisting of a certain number of series of contacts and an equal number of series of wipers, means for setting the wipers in accordance with the position of the impulse receiving organ, contacts disposed for connecting the calling line to a certain determined series of wipers, switching relays for operating the said contacts, the said relays connected to certain contacts of the impulse receiving organ, a slow act-

- ing relay in a circuit receiving impulses of current, contacts operated by the said relay and arranged for short-circuiting the switching relays during the train of impulses.
- 5 6. In an automatic telephone system as claimed in claim 5 an extra row of contacts in the bank of the impulse receiving organ, a wiper associated with the said row of contacts, a row of control contacts in the bank 10 of the connecting mechanism, a control wiper associated with the control contacts and moving with the wipers of the connecting mechanism, each contact of the said row being connected to a certain determined contact of the extra row of contacts in the bank 15 of the impulse receiving organ, an operating circuit for the connecting mechanism comprising an interrupter, the said relay being connected to the control wiper.
- 20 7. In an automatic telephone system as claimed in claim 5 an extra row of contacts in the bank of the impulse receiving organ, a wiper associated with the row of contacts, the said wiper being electrically connected 25 to the other wipers of the impulse receiving mechanism, a row of control contacts in the bank of the connecting mechanism, a control wiper associated with the control contacts and moving with the wipers of the 30 connecting mechanism, each contact of the said row being connected to a certain determined contact of the extra row of contacts in the bank of the impulse receiving organ, an operating circuit for the connecting 35 mechanism comprising an interrupter, a relay for operating this interrupter, the said relay being connected to the control wiper and arranged so as to be energized in series with one of the switching relays.
- 40 8. In an automatic telephone system, as claimed in claim 1, an operating circuit for the connecting mechanism, means for immediately closing this circuit after receiving the first impulse.
- 45 9. In an automatic telephone system as claimed in claim 1 an operating circuit for the connecting mechanism, a contact in this circuit arranged to be closed when the impulse receiving organ leaves its normal position.
- 50 10. In an automatic telephone system, a calling line, groups of called lines, an electric impulse sending device, an impulse receiving organ for the said impulses, a single 55 motion connecting mechanism for connecting the calling line to a line in the called group, the said connecting mechanism consisting of a certain number of series of wipers, the lines of each group of called lines 60 being connected to the successive contacts in a series of contacts, two operating circuits for the connecting mechanism, each one comprising an interrupter, means for operating the interrupter in one of these circuits when the 65 connecting mechanism is set on the first line of the called group, means for operating the interrupter in the other circuit when the connecting mechanism is set on an idle line in the called group and means for inserting a certain series of wipers in the connecting 70 circuit according to the position of the impulse receiving organ.
11. In an automatic telephone system, a calling line, a called line, an electrical impulse sending device, an impulse receiving 75 organ consisting of a rotary switch having several rows of switching contacts, each row containing the same number of contacts and wipers, a single motion connecting mechanism, for connecting the calling line to a line in the called group, the said connecting mechanism consisting of a certain number of series of connecting and test contacts, connecting and test wipers, a row of control contacts, a control wiper, the lines in each 80 called group being connected to successive connecting and test contacts of the same series of contacts, each contact in the row of control contacts being connected to a certain determined contact in the row of control 85 contacts of the impulse receiving organ, a first operating circuit for the connecting mechanism comprising an interrupter, the said relay being connected to the control wiper, a second operating circuit for the 90 connecting mechanism, comprising another interrupter, a test relay for controlling the second interrupter the said test relay being in a circuit comprising one of the test wipers and a test contact; contacts 100 disposed for connecting the calling line to a certain determined series of connecting and test wipers, switching relays for operating these contacts, the said relays being connected to certain switching contacts of 105 the impulse receiving organ, means for rendering inoperative the second operating circuit until the end of the train of impulses and as long as the first operating circuit is closed.
- 110 12. In an automatic telephone system as claimed in claim 11, a contact disposed in the second operating circuit of the connecting mechanism, a contact in the circuit of the test relay, a slow acting relay inserted 115 in an impulsive circuit, disposed for holding these contacts open during the impulses, another contact in the second operating circuit, another contact in the circuit of the test relay the said contacts being closed by the 120 energization of the stop relay.
- 125 13. In an automatic telephone system as claimed in claim 11, an interrupter for the first operating circuit of the connecting mechanism, means for opening the said interrupter when the selector is in normal position, a contact for short circuiting this interrupter, a slow acting relay inserted in an impulsive circuit arranged for closing the said contact during the train of impulses.

14. In an automatic telephone system as claimed in claim 1, a calling line comprising connecting and test conductors, two interrupters in series on the test conductor, a relay connected to the connecting conductors and disposed for operating one of the said interrupters, and means for opening the second interrupter when the impulse receiving mechanism is in off normal position.
15. In an automatic telephone system, a calling line comprising connecting and test conductors, a called line, an electrical impulse sending device, an impulse receiving organ, consisting of a rotary switch having several rows of switching contacts, each row having an equal number of contacts, a row of control contacts, wipers for electrically connecting homologous contacts in the said row of contacts, a single motion connecting mechanism for connecting calling and called lines, the said connecting mechanism consisting of a certain number of series of connecting contacts, connecting wipers, a row of control contacts and a control wiper for engaging the said control contacts, each contact of the row of control contacts being connected to a determined contact in the row of control contacts of the impulse receiving organ, an operating circuit for the connecting mechanism comprising an interrupter, a stop relay for operating the said interrupter, the said relay being connected to the control wiper; contacts arranged for connecting the calling line to a determined series of wipers, switching relays for operating these contacts, connected to certain switching contacts of the impulse receiving organ, an interrupter inserted in series with the test conductor of the calling line, a relay connected to the connecting conductor of the calling lines and arranged for operating the said interrupter, two fixed contacts separating the test conductor into two parts, and arranged to be connected together by a wiper of the impulse receiving organ in normal position.
16. In an automatic telephone system as claimed in claim 1 a calling line comprising connecting and test conductors, three interrupters inserted in series with the test conductor, a relay connected to the test conductor, a relay connected to the connecting conductor and arranged for operating one of these interrupters, means for opening the second interrupter when the impulse receiving organ is in off normal position and means for opening the third interrupter when the connecting mechanism is in off normal position.
17. In an automatic telephone system as claimed in claim 15, another interrupter in series with the test conductor of the calling line and arranged to be operated mechanically by the connecting mechanism in such a way that the interrupter is opened when the said mechanism is in off normal position.
18. In an automatic telephone system as claimed in claim 11, a busy tone machine, a contact for connecting this machine to the calling line, the said contact arranged for being controlled by the stop relay.
19. In an automatic telephone system, a calling line, a called line, a device for sending series of impulses, several impulse receiving organs, means by which each impulse receiving organ is operated by a series of impulses of corresponding order, a single motion connecting mechanism for connecting calling and called lines the said mechanism consisting of a certain number of series of contacts and the same number of series of wipers, means by which the setting of the wipers of the connecting mechanism is obtained by successive degrees determined by the respective settings of the various impulse receiving organs, means for inserting a certain series of wipers in the connecting circuit according to the setting of the impulse receiving organs.
20. In an automatic telephone system as claimed in claim 19, an operating circuit for the impulse receiving organs, switching arrangements for successively connecting this circuit to the various impulse receiving organs and arranged for being operated between each series of impulses, a slow acting relay in series with the said operating circuit and controlling the said switching arrangement.
21. In an automatic telephone system, a calling and a called line, a device for sending series of impulses, several impulse receiving organs, each one consisting of a rotary switch having fixed contacts and wipers, a single motion connecting mechanism for connecting calling and called lines, the said mechanism consisting of a certain number of series of contacts and connecting wipers, a row of control contacts and a control wiper, the said control contacts being connected to certain determined contacts of the various impulse receiving organs, an operating circuit for the connecting mechanism, an interrupter in this circuit, a stop relay for controlling the said interrupter and connected to the control wiper, an operating circuit for the impulse receiving organs, a switching arrangement for successively connecting this circuit to the various impulse receiving organs, a slow acting relay in series with the said circuit of the impulse receiving organs, a control relay for the said switching arrangements, arranged to be operated when the slow acting relay is in normal position and the stop relay energized, means for opening the circuit of the stop relay during the reception of the following series of impulses and means for inserting a certain series of wipers in the connecting circuit according

to the setting of the impulse receiving organs.

22. In an automatic telephone system, a calling and a called line, a device for sending series of impulses, several impulse receiving organs, means by which each impulse receiving organ is operated by the series of impulses of corresponding order, a single motion connecting mechanism for connecting calling and called lines, an operating circuit for the said mechanism, a stop relay controlling this circuit, means by which the setting of the connecting mechanism is obtained by successive degrees determined by the respective setting of the various impulse receiving organs, means by which the circuit of the stop relay is not opened after each setting of the connecting mechanism unless the number of impulses in the following series exceed a determined number.

23. In an automatic telephone system as claimed in claim 22, impulse receiving organs, each having a wiper and contacts, a conductor connecting the wiper of each impulse receiving organ to a certain number of the first contacts of the following impulse receiving organs, this conductor being comprised in the circuit of the stop relay.

24. In an automatic telephone system as claimed in claim 22, impulse receiving organs, each having a wiper and contacts, a single motion connecting mechanism, having rows of connecting contacts and wipers and a row of control contacts and wiper, conductors connecting the contacts of the first impulse receiving organ to certain contacts in the row of control contacts, conductors connecting contacts of the second impulse receiving organ to certain intermediate control contacts, and so on, each of the said control contacts corresponding to the first line in the group of lines determined by this control contact.

25. In an automatic telephone system as claimed in claim 19, a certain number of series of test contacts and wipers in the connecting mechanism, means for raising to a determined potential the test contact of the called line, this potential being different according to the free or engaged condition of the said line, two relays connected in parallel to the test wiper on the one hand and respectively to the opposite poles of a source of energy on the other, means for rendering this circuit inoperative until the wipers of the connecting mechanism are set on the called line, a circuit controlled by the first relay for connecting the calling and the called line, a circuit controlled by the second relay for connecting the calling line to a busy-tone machine.

26. In an automatic telephone system as claimed in claim 19, a certain number of se-

ries of test contacts and wipers on the connecting mechanism, means for raising to a determined potential the test contact of a called line, this potential being different according to the free or engaged condition of the said line, two relays connected in parallel to the test wiper on the one hand and respectively to the opposite poles of the source of energy on the other, an interrupter in the circuit of each of these relays, a relay for controlling these interrupters, means for energizing this relay when the wipers of the connecting mechanism are set on the called line.

27. In an automatic telephone system, a calling line, groups of called lines, a device for sending series of impulses, several impulse receiving organs, means by which each impulse receiving organ is operated by corresponding series of impulses of corresponding order, a single motion connecting mechanism for connecting a calling line to an idle line in a called group, the said mechanism consisting of a certain number of series of connecting contacts and wipers and test contacts and wipers, an operating circuit for the said mechanism, a stop relay controlling this circuit, means by which the setting of the connecting mechanism is obtained by successive degrees determined by the respective settings of the different impulse receiving organs, means for inserting a certain series of wipers in the connecting circuit, according to the position of the impulse receiving organs, means for raising to a determined potential the test contacts of the lines in the called group according to the free or engaged condition of the lines, the test contact of the called lines connected to one of the poles of the source of energy in series with a resistance, this resistance being lower for the last line in a group, two relays connected in parallel to the test wiper on the one hand and respectively to the opposite poles of the source of energy on the other, means for establishing these circuits when the wipers of the connecting mechanism are set on the first line of the called group; one of these relays being shunted when the called line is free, the two relays being energized in series if the called line is engaged and is not the last line of a group, and the second relay being shunted if the engaged called line is the last one of the group, in order to connect the calling line to the called line in the first case, to produce an automatic selection in the second and to give the busy tone to the calling line in the third case.

28. In an automatic telephone system, calling lines comprising connecting and test conductors, a called line, an electrical impulse sending device, an organ for receiving the said impulses, several single motion connecting mechanisms for connecting calling

- and called lines, each of these mechanisms consisting of a certain number of series of contacts and an equal number of series of wipers, a connecting relay in series with the 5 test conductor of the calling line and operating contacts for connecting a calling line and the corresponding connecting mechanism to the impulse receiving organ, means for energizing this connecting relay when 10 the calling line is connected to the connecting mechanism, means for setting the wipers of the said mechanism according to the position of the 45 impulse receiving organ, means for inserting a certain series of wipers in the connecting circuit according to the position of the impulse receiving organ, an interrupter in series with the test conductor of the calling 50 lines in the impulse receiving organ, a relay in the circuit of the calling line arranged to open this interrupter when the impulse receiving organ is connected to a calling line. 15 31. In an automatic telephone system, calling lines comprising connecting and test conductors, a called line, a device for sending series of impulses, several impulse receiving organs, means by which each impulse receiving organ is operated by a series 60 of impulses of corresponding order, several single motion connecting mechanisms for connecting calling and called lines each of the said mechanisms consisting of a certain number of series of contacts and wipers, a 65 connecting relay in series with the test conductor of the calling line, and operating contacts for connecting a calling line and the corresponding connecting mechanism of the impulse receiving organs, means for energizing 70 this connecting relay when the calling line is connected to the connecting mechanism, means by which the setting of the connecting mechanism is obtained by successive degrees determined by the respective 75 settings of the various impulse receiving organs, means for inserting a certain series of wipers in the connecting circuit according to the position of the impulse receiving organs, an interrupter in series with the test conductor of the calling lines in the impulse receiving organs, a relay in the circuit of the calling line arranged to open this interrupter when the impulse receiving organ is 80 connected to a calling line. 85
30. In an automatic telephone system, calling lines comprising connecting and test conductors, a called line, an electrical impulse sending device, an organ for receiving the said impulses having contacts and wipers, several single motion connecting mechanisms for connecting calling and called lines each of these mechanisms consisting of a certain number of series of connecting contacts and wipers and a row of control contacts and a control wiper, conductors connecting homologous contacts in the row of control contacts to the contacts of the impulse receiving organ, a connecting 35 relay in series with the test conductor of the calling line and operating contacts for connecting a calling line and the corresponding mechanism to the impulse receiving organ, means for setting the wipers of the said 40

In testimony whereof I have signed my name to this specification.

ANTOINE BARNAY.
